UNITED STATES PATENT OFFICE

WILLIAM OWEN, OF PITTSBURGH, PENNSYLVANIA, ASSIGNOR TO PITTSBURGH PLATE GLASS COMPANY, A CORPORATION OF PENNSYLVANIA

APPARATUS FOR MAKING PLATE GLASS

Application filed October 22, 1930. Serial No. 490,440.

The invention relates to apparatus for making plate glass by an intermittent casting or rolling operation and then carrying the glass continuously forward through a leer preferably of the roller type. In such an operation, it is desirable to roll the sheet at a relatively high rate of speed and then carry such sheet through the leer at a much reduced rate, as otherwise an exceedingly long leer would be required. The present invention has for its object the provision of an improved means for carrying out this operation including the step of matching the successive sheets so that they may be made to follow each other in the leer with as short a space therebetween as may be found desirable. One embodiment of the invention is shown in the accompanying drawings, wherein:

20 Figure 1 is a plan view somewhat diagrammatic in character. Fig. 2 is a longitudinal section. And Figs. 3 and 4 are enlarged detail views of the receiving table, Fig. 3 being a plan view and Fig. 4 a vertical section.

25 Referring to the drawings, A is a rolling apparatus comprising a pair of rolls, between which a pot of glass is cast, carried by a car B and movable longitudinally of a roller runway or table C during the latter part of the casting operation; D is a roller leer, E is a line shaft extending the length of the leer and runway and arranged to drive the leer rolls, the runway rolls, the sizing rolls, and the car which carries the sizing rolls, such line shaft 30 being driven from its left hand end by a motor which is not shown; and F is a shield or hood of sheet metal lying at one end of the runway and movable with the car B, so that it telescopes into the leer at one end and into the runway casing I at its other hand.

35 The roller leer has its runway made up of sets of rolls 1, 2, 3, etc. each set being driven by a chain 4 passing around sprockets on the ends of the rolls. Each chain is driven from the line shaft E through the intermediary of the spur gears 5, reduction gearing in the casing 6 and the shafts 7 which carry sprockets 40 engaging the chains 4. The rollers 8 which make up the runway C are driven by a chain 9 passing around sprockets on the ends of

the rolls and also around a drive sprocket on the end of the shaft 10. The shaft 10 is driven from the shaft E at low speed through the electric clutch 11, gears 12 and 13, and reduction gearing in the casing 14. Such 55 shaft is driven at a higher speed in a reverse direction during the casting operation, as later described, through the clutch 11a, gears 15a, and 16, and the reduction gearing in the casing 14. The shift from high to low speed 60 may thus be accomplished by shifting the clutches 11 and 11a, which in one case locks the gear 12 to the shaft E and in the other case locks the gear 15 to such shaft.

65 The rolls constituting the runway C are interspersed with coolers 17 (Figs. 3 and 4) through which air or water may be circulated carrying the sectional plates 18, the sectional construction being employed to avoid warping. The rolls are cooled by circulating air 70 or water therethrough, and additional cooling may be provided in the form of the air supply pipes 19 perforated along their upper sides.

75 The sizing rolls 20 and 21 are hollow and water cooled in the usual way. The roll 21 is driven by a chain 22 passing around a sprocket on the end of the roll and around loose sprockets on the shafts 23, 23, one of which may be locked to its shaft by the clutch 80 24. The shafts 23, 23 are driven from the shaft E through the spur gears 25, 25 and reduction gearing in the casings 26, 26. The roll 20 is driven from the roll 21 by means of the intermeshing spur gears 27.

85 The track for the car is in the form of a pair of racks 28, 28 which are engaged by the wheels of the car which are in the form of spur gears 29. One pair of these gears is provided with a shaft carrying a sprocket over whose upper side in driving engagement therewith passes the chain 30. This chain passes around sprockets loose on the shafts 23, 23, one of which may be locked to its shaft by the clutch 31. This gearing arrangement provides for 90 moving the car to the right. Provision is also made for moving the car to the left. This is accomplished through the shaft carrying the spur gears 29. A second sprocket is provided upon this shaft over whose lower side in driv- 100

- ing engagement therewith passes the chain 32. This chain passes around sprockets loose on the shafts 23, 23, one of which may be locked to its shaft by the clutch 33. Beneath the rolls 20 and 21 is a hollow apron 34 suitably cooled and arranged to direct the sheet of glass formed between the rolls toward the end of the runway remote from the leer. The starting position of the apparatus is with the car and sizing rolls at the full line position shown in Fig. 2. When the glass from the pot 35 is poured into the hopper 36, the sizing rolls 20 and 21 are rotated at casting speed as are also the rolls 8 of the runway, such speed being by way of illustration about 30 feet per minute. This continues until the end of the sheet 37 approaches the position adjacent the end of the runway, as indicated in Fig. 2. The car B carrying the sizing rolls is now moved to the right and the direction of rotation of the runway rolls 8 is reversed, such rolls now being at annealing speed corresponding to that of the leer rolls 1, 2, 3, etc. This speed may be, for example, $7\frac{1}{2}$ feet per minute. In order that the sheet may be deposited upon the runway without stretching or wrinkling, the speed of movement of the car to the left would have to be $37\frac{1}{2}$ feet per minute, which movement would continue until the glass in the hopper is exhausted and the sheet completed, at which time the car would occupy the dotted line position G of Fig. 2. The car is now moved back to starting position and after the sheet reaches the position marked H, a second casting operation is initiated, the operation being carried out as heretofore described. By timing this second operation properly, the second sheet may be deposited with its left hand end closely adjacent the rear end of the first sheet. This matching or close spacing of the sheets is possible because of the mounting of the sizing rolls upon the car for movement to the left and because of the reversal of rotation of the runway rolls 8. The result achieved is a full utilization of the leer space, which could not be secured if the sizing rolls were not mounted for movement longitudinally of the leer and runway.
50. What I claim is:
1. Apparatus for making a sheet of glass comprising a leer having continuously operating forwarding means, a runway at the end of the leer, means for driving said forwarding means in the same direction and at the same speed as the leer forwarding means, or in a reverse direction at a higher rate of speed, a car mounted for movement back and forth along the runway, means for moving the car, a pair of sizing rolls carried by the car above the runway, an apron on the car below the rolls for receiving the sheet formed between such rolls, such apron being directed toward the end of the runway remote from the leer, and means for rotating

the sizing rolls as the car is moved along the runway toward the leer at a rate of peripheral speed which is substantially equal to the rate of movement of the car less the rate of movement of the leer rolls. 70

2. Apparatus for making a sheet of glass comprising a leer having continuously operating forwarding means, a runway at the end of the leer, means for driving said forwarding means in the same direction and at the same speed as the leer forwarding means, or in a reverse direction at a higher rate of speed, a car mounted for movement back and forth along the runway, means for moving the car, a pair of sizing rolls carried by the car above the runway, an apron on the car below the rolls for receiving the sheet formed between such rolls, such apron being directed toward the end of the runway remote from the leer, a casing surrounding the runway, a shield extending over the forward end of the leer movable with the car and arranged to telescope inside the casing, and means for rotating the sizing rolls as the car is moved along the runway toward the leer at a rate of peripheral speed which is substantially equal to the rate of movement of the car less the rate of movement of the leer rolls. 80 85 90

3. Apparatus for making a sheet of glass comprising a roller leer, a roller runway at the entrance end of the leer, means for operating said rolls in the same direction and at annealing speed, means for operating the rolls of the runway in the reverse direction 95 at a higher rate of speed than annealing speed, a car mounted for movement back and forth along the runway, a pair of sizing rolls carried by the car above the runway, an apron on the car for receiving the sheet formed between the rolls directed toward the end of the runway remote from the leer, means for rotating the sizing rolls at a rate of peripheral speed which is greater than that of the leer rolls, and means for moving the car toward the leer during the latter part of the casting operation at a rate of speed which is substantially equal to the rate of peripheral speed of the sizing rolls plus that of the leer rolls. 100 105 110 115

In testimony whereof, I have hereunto subscribed my name this 17 day of October, 1930.

WILLIAM OWEN.
